UNITED STATES PATENT OFFICE.

FRANZ SCHIAEFER, OF CREFELD, GERMANY.

STEAM MASHING APPARATUS FOR BREWERY PURPOSES.

SPECIFICATION forming part of Letters Patent No. 649,216, dated May 8, 1900.

Application filed July 12, 1899. Serial No. 723,551. (No model.)

To all whom it may concern:

Be it known that I, FRANZ SCHAEFER, engineer, a subject of the Emperor of Germany, residing at 104 Westwall, Crefeld, in the Kingdom of Prussia and Empire of Germany, have invented certain new and useful Improvements in Steam Mashing Apparatus for Brewery Purposes, of which the following is a full, clear, and exact description.

10 In practice special steam apparatus is used for steam mashing for brewery purposes, which as a rule consists of a system of tubes through which the steam is conducted, and in more modern plants these tubes are continuously rotated in the mash-tun.

15 A leading disadvantage in the mashing systems now in use is that the mash adheres to the rotating pipes when it is being warmed up, a defect occasioned by the insufficient movement of the mash in itself and relatively to the heating-surface. As a rule it is impracticable to employ scrapers rotating in contact with the walls of the mash-tun, for the reason that they impede the rotation of the 20 steam-pipe system. The pipes must be arranged in some such manner as that shown in the German Patent No. 35,237, where they consist of bent U-shaped pieces which are fastened at intervals to hollow collars on a 25 solid axle passing centrally through the apparatus, which collars also serve to conduct the steam. This contrivance, however, has the disadvantage that the steam cannot pass unimpeded through the whole pipe system; 30 but must at intervals return to the collars on the axle, which to some extent constitute the steam-chest. The natural consequence of this is that the temperature is not the same in the last pipe as in the first, owing to the 35 repeated interruptions to the passage of the steam. A uniform working of the mash is therefore impossible. A further and greater disadvantage is that in steaming the mash in such an apparatus it frequently lies unstirred 40 against the smooth wall of the rotating steam-chest in consequence of the slight amount of friction, whereby the possibility occurs of the mash easily burning, owing to the heat generated in this place, and a uniform mashing 45 cannot take place, because there is much greater generation of heat in this place than at the periphery.

The object of the present invention is to obviate these two great disadvantages as much as possible and is attained by passing the steam through a steam-chest with double walls, forming chambers adapted to be filled with non-conducting material and a similarly-constructed steam-pipe into the rotating pipes, which are arranged in such a serpentine manner as to form separate parallel planes. At the same time an unbroken circulation of the steam through all the convolutions of the pipe system from top to bottom is insured. In an apparatus thus constructed the steam-pipe 65 system can be made to rotate conveniently between the several scrapers.

The improvement is illustrated in the accompanying drawings.

Figure 1 is a sectional elevation of a steam mashing apparatus embodying this improvement. Fig. 2 is a plan of the same, partly in horizontal section. Fig. 3 is a detail perspective view of one of the steam-coils hereinafter described.

75 Steam is supplied through a pipe *a*, connecting with an interior pipe *a'*, forming part of the rotary apparatus and turning in a suitable stuffing-box *s*. The interior pipe *a'* is surrounded by a second pipe *b*, which expands below into a dome-shaped covering for the steam-chest *b'*. The latter is also provided with a double wall *b*², so that between this and the inner wall *b*³ an insulating-space *f* results. This insulating-space, as also that 80 around the steam-pipe *a'*, is in practice filled with some material calculated to impede heat radiation in order that the heat may be diminished on the outer surface of the rotary steam-chest. By this means the mash, which, as 85 was pointed out in the introduction, receives little or no stirring movement in this place, is prevented from burning and uniform mashing is insured. The steam-chest is constructed with a top chamber *b*⁴, separated from the 90 main body by a partition *p*. The steam-pipe *a'* delivers into this top chamber *b*⁴, and with it the first section *c'* of the steam-coil *c* connects. The circulating steam passes out from the top chamber *b*⁴ of the steam-chest 95 into the rotating coil, which is arranged in a serpentine manner, so that the first coil-sections *c'*, here shown four in number, extend radially outward, each connecting by a bend 100

with the second section c^2 , which extends inward nearly to the center, where it is bent, and extends outward again in the second plane as the third pipe-section c^3 . In the same horizontal plane it turns inward again, is again led downward, and again outward as the coil-section c^4 , and backward as the last coil-section c^5 , which is connected with the steam-chest b' near its lower end. The inward and outward circulation pipe-sections thus lie above each other. In this way the pipe-planes when rotated move between the fixed scrapers g , prevent burning, and produce an intimate mixing, thus insuring a uniform mashing.

15 The whole apparatus, consisting of the steam-chest and pipe system, is set in motion by the band-pulley h , the shaft of which connects by bevel-pinions 2 with the vertical axle m of the rotary steam-chest b' . The lower journal end of the axle m is also made hollow, so that the steam may pass off through it and the pipe n .

20 The following is what I claim and desire to secure by Letters Patent:

25 1. The steam mashing apparatus for brew-

ing, constructed as herein described with a rotary steam-chest b' surrounded by an outer wall b^2 inclosing a chamber f to reduce conduction of heat and a steam-coil c connected with said steam-chest and formed of convolutions arranged radially in a number of parallel planes, in combination with fixed scrapers g between which the radial arms of the steam-coil revolve, as explained.

2. The combination of the induction steam-pipe a rotary steam-chest b' inclosing walls b and b^2 steam-coil c , consisting of a number of convolutions $c' c^2 c^3 c^4$ radially arranged in parallel planes and communicating with the rotary steam-chest, hollow shaft m exit-pipe n and suitable scrapers g between which the arms of the steam-coil revolve substantially as described.

In witness whereof I subscribe my signature in presence of two witnesses.

FRANZ SCHAEFER.
